UNITED STATES PATENT OFFICE.

SAMPSON BACHRACH, OF CHICAGO, ILLINOIS, ASSIGNOR TO JANET S. BACHRACH, OF CHICAGO, ILLINOIS.

DISPLAY-CABINET.

1,012,965.

Specification of Letters Patent.

Patented Dec. 26, 1911.

Application filed April 21, 1910. Serial No. 556,698.

To all whom it may concern:

Be it known that I, SAMPSON BACHRACH, a citizen of the United States, residing at Chicago, in the county of Cook and State 5 of Illinois, have invented a new and useful Improvement in Display-Cabinets, of which the following is a specification.

My invention relates particularly to display cabinets adapted to be placed upon 10 counters, show-cases, etc., to contain and display small articles of merchandise, such as collar-buttons and other small articles of jewelry.

My primary object is to provide a cabinet 15 of the character indicated of simple and improved construction and thoroughly adapted to its purpose.

The invention is illustrated in its preferred embodiment in the accompanying drawing, 20 in which—

Figure 1 represents a broken front elevational view of a display cabinet constructed in accordance with my invention; Fig. 2, a section taken as indicated at line 2 of Fig. 25 1, the dotted lines showing the closure of the cabinet in the open position; and Fig. 3, a broken perspective sectional view showing the manner in which the curved glass sectors employed are united and framed.

In the construction illustrated, A represents a half-circular base upon which are mounted half-circular tiers 1 of receptacles 30 2; and B, a closure composed of a back section 3 joined by hinges 4 to a back-section 5 which rises from the rear upper margin of the base A, said back-section 3 carrying a curved glass wall 6 which is preferably approximately in the form of a quarter of a spherical shell. The glass wall is composed 35 40 of curved sectors 7 which are united at their meeting edges by meridional metallic connecting members 8, the corresponding free edges of the flanking sectors 7 being bound by meridional members 8^a. The members 8 and 8^a meet and are united to a cap-member 9 45 having a shank 10 connected with the central upper portion of the back-section 3, it being understood that the back-section 3 has a curved upper edge, whose curvature 50 is continued at the ends of the back-section 5, the curved edge of both members taken together forming approximately a half-circle. The meridional ribs 8 and 8^a are joined at their lower ends by a half-circular rib 11,

so that the glass segments are well supported 55 and framed. The member 9 carries an upwardly-projecting stud 12 upon which is mounted a handle 13, which, in the illustration given, is in the form of a collar-button the base of which rests upon the member 9. 60

The tiers 1 of the receptacles are located in successively elevated planes from front to rear, being grouped in front of and curved about an axis corresponding approximately with the center line of the back of 65 the structure. The back-section 3 may be composed of a board 14 and a mirror 15 disposed in front of said board and having its reflecting surface turned forwardly, so that the contents of the receptacles will be reflected from the mirror. The base A has a curved projecting margin 16 which is outside of or in front of the lower tier 1 of receptacles and has on its upper surface a half-annular felt pad 17 upon which the 70 lower edge of the frame of the glass portion of the closure rests. Secured to the back-section 5 is a bracket or brackets 18 having a rearwardly-inclined, felt-covered upper surface 19 adapted to support the closure 75 when the latter is in the open position, thus providing for ready access to all of the receptacles of the cabinet.

Fig. 3 shows one manner in which the glass sectors may be united by the ribs 85 8. According to the construction shown, two U-shaped binding-members 20 are employed which embrace the adjacent edges of the glass members and have their backs united by solder 21. The lower binding- 90 member 11 is composed of a similar U-shaped member 22 having upturned flanges and to whose outer surface is soldered a wire member 23. The marginal ribs 8^a are equipped with bracket-members, or clips, 24, which 95 have downturned projections which embrace the rear surface of the back-section 3 to which they are secured. Thus, the frame of the glass portion of the closure is firmly united to the back-section 3 by the clips 24 100 and clip 9.

It may be noted that owing to the hinging of the back-section which carries the glass cover at some distance above the lower edge of the glass cover, the structure is more 105 evenly balanced when in the open position, so that the danger of the structure tipping backward is obviated. Inasmuch as the de-

vice is likely to be placed near the rear edge of a counter or show-case, this is regarded as an important feature. It is noted, also, that the receptacle-structure 5 rises some distance above the line of hinging of the cover-carrying back-section. Moreover, the framing carried by the back-section 3 is adapted to contribute great strength to the glass-cover.

10 The frame for the glass cover may be constructed in any desired manner, that illustrated being used by preference.

15 The form and construction of the receptacles mounted on the base A may be according to fancy or desire, the foregoing detailed description having been given for clearness of understanding only. Hence, the appended claim is to be construed as

broadly as permissible in view of the prior art.

20 What I regard as new, and desire to secure by Letters Patent, is—

A cabinet comprising a base, a fixed back-section, a movable back-section hinged to said fixed back-section some distance above 25 the base, a cover united to the free edge-portion of said movable back-section and having its lower margin extending beneath the line of hinging of said movable back section and adapted to bear upon said base, 30 and a stop for limiting the rearward movement of the cover.

SAMPSON BACHRACH.
